UNITED STATES PATENT OFFICE.

ENGLAND J. BARKER, OF CHICAGO, ILLINOIS.

EXTRACTING MECHANISM FOR AUTOGRAPHIC REGISTERS.

1,279,497.

Specification of Letters Patent. Patented Sept. 24, 1918.

Application filed August 26, 1916. Serial No. 117,029.

To all whom it may concern:

Be it known that I, ENGLAND J. BARKER, a citizen of the United States, residing at Chicago, in the county of Cook and State of Illinois, have invented new and useful Improvements in Extracting Mechanism for Autographic Registers, of which the following is a full, clear, and exact description.

10 My invention relates to new and useful improvements in autographic registers, and particularly to registers of the kind having mechanism for assisting in extracting therefrom the paper strips used in connection with the same for preserving written records of business and other transactions.

Heretofore, the transverse stretch of metal forming the end of the open rectangular frame or cover which is placed next and 20 substantially parallel to the discharge end of an autographic register, and which covers over the margins of the platen, over which the strips of paper are drawn after they have been written upon, was made very 25 thin, and a superposed tearing-blade connected to the top of the side-frames of the register at the discharge end of the same immediately back of which this very thin stretch of the cover reposed. In the old 30 type of autographic registers this tearing-blade was stationary, but in the more recent types in which paper extractor mechanism is employed, the tearing-blade is adapted to move forward together with the under-

35 lying plate a limited distance after the extracting mechanism is operated, substantially as set forth in application for Letters Patent of the United States, filed by me May 25, 1916, Serial Number 99,732. This 40 thin end stretch of the cover is liable to become bent and effect the operation of the register and the alinement of the paper strips in transit from the machine.

The object of my invention is to combine 45 the end stretch of the cover and the tearing-blade in one piece, particularly when used in connection with my improved extracting mechanism and thus greatly strengthen the same and avoid the possibility of the said 50 end of the cover bending or warping. Another object of my invention is to use such a cover having an integral tearing-blade in connection with extracting mechanism employing pins that project up through and 55 move longitudinally in longitudinal slots in

the discharge end portion of the platen, so that when said pins are at the limit of their forward or extracting movement and are withdrawn from the perforations in the paper strips, the platen will support the extracted end of said strips while the pins are being withdrawn from the perforations therein. These and other objects are accomplished by means of my improvements, substantially as hereinafter fully described, 60 and as particularly pointed out in the claims.

In the drawings:

Figure 1 is an end view of the upper broken away portion of an autographic 70 register embodying my invention.

Fig. 2 is a side elevation of the same.

Fig. 3 is a side view of the side of the register opposite that shown in Fig. 2.

Fig. 4 is a vertical longitudinal section 75 taken on dotted line 4-4, Fig. 1.

Fig. 5 is a vertical longitudinal section taken on dotted line 5-5, Fig. 1.

Fig. 6 is a similar section taken on dotted line 6-6, Fig. 1. 80

Fig. 7 is a similar section taken on dotted line 7-7, Fig. 1.

Fig. 8 is a horizontal longitudinal section taken on dotted line 8-8, Fig. 1, looking 85 in the direction of the arrows.

Fig. 9 is a plan view of the broken away end portion of said register showing the cover raised from the platen, or in other words, opened.

Referring to the drawings, A, A, represent the corresponding side-frames of an autographic register; B the platen or bed connecting the upper edges of said side-frames, and C represents the rectangular open frame or cover which is hinged to the 90 outer longitudinal edges of the trough or magazine D (concerning which further description is unnecessary) and is adapted to be closed down over the margins of the platen so as to leave an open space for the 100 convenience of the operator to write such records or memoranda upon the paper strips as he desires. At its discharge end, the platen extends practically to the end edges of the overhang of the ends of the side-frames and it is provided with longitudinal slots 9, 9, on either side of the center thereof that extends back from the end edge of the platen a suitable distance, substantially 105 as shown in the drawings.

The transverse end member of cover C adjacent the discharge end of the register is, comparatively speaking, quite wide, and is, preferably, reinforced by a steel blade 10 which is secured to its underside by rivets or otherwise. The forward transverse edge of this blade projects beyond the corresponding edge of end member *c* of the cover and is sharpened to form a tearing-blade upon which the strips of paper are torn off in the usual manner after they have been withdrawn from the register.

The paper strips used in the register embodying my invention are provided with two longitudinally arranged series of perforations, and the perforations of each series are at equal distances apart throughout their lengths, and the perforations of one series are arranged to pair with the corresponding perforations in transverse alignment therewith. These perforations are so located that when the paper is withdrawn they will move longitudinally over and register with slots 9, 9, in the discharge end of the platen, and be engaged by vertically disposed pins 14, 14, which latter pass up through the perforations and enter overhead longitudinal grooves 15 made in the underside of tearing-blade 10.

Pins 14, 14 are mounted upon the forward ends of longitudinally disposed flat springs 16, 16, the rear ends of which are suitably secured to longitudinally disposed flat metal bars 17 that constitute the side-members of a carrier-frame, and these side-members are held flat against the underside of the platen by means of headed screws 18, 18 and 19, 19, that pass through longitudinal slots 20 and 21 into the platen. These side-members 17, 17, are connected near their rear ends by a cross-bar 22 and the entire carrier-frame is normally kept at the limit of its rearward movement by means of a coiled contraction spring 23, one end of which is secured to cross-bar 22 and the other end to a leg or screw secured on and depending from the underside of the platen. Pins 14 pass up through suitable openings 25 made in the forward portions of members 17, and the entire carrier-frame is moved forward so as to enable pins 14 that engage the perforations in the paper to move said paper strips forward a sufficient distance so that the end edges thereof can be grasped by the hand and held when said pins are withdrawn downward out of said perforations and returned to their original positions.

The forward ends of side-members 17, 17, have arms 26 secured to the underside thereof that project downward a suitable distance and have their lower portions bent forward, substantially as shown in Fig. 5 of the drawings. The rear side of these arms are engaged by anti-friction rollers 27 that are journaled in the upper ends of hook-

shaped arms 28 and these arms are secured to and project from a transverse rock-shaft 29 the ends of which are journaled in suitable bearings in the side-frames of the register near the forward edges thereof. One end of this rock-shaft 29 extends through its bearings a suitable distance and has an arm 30 secured to the extremity thereof, and this arm 30 projects in a forwardly direction from said shaft 29 and is provided with a flattened tread 31 on the upper edge of its forward end. Arm 30 is depressed to rock shaft 29 so this tread is engaged by an anti-friction wheel 32 journaled in the lower end of a plunger 33, which latter extends up through suitable guide-bearings 34, made integral with and projecting from end-member *c* of cover C to a suitable point above the same where it is provided with a head or knob 35 by means of which it can be manipulated. This causes arm 30 to move downward and thus moves rock-shaft 29 and causes arms 28 to engage arms 26 depending from the longitudinal members 17 of the carrier-frame and moves the latter forward. Rock-shaft 29 is restored to its normal position by means of a coiled torsion spring 36 surrounding the same between arm 30 and the adjacent side-frame of the register,—one end of said spring being secured to said shaft and the other to said side-frame.

The mechanism for causing the pins to move downward when they shall have reached the limits of their forward movement is the same as that described and claimed by me in the aforesaid pending application.

When arm 30 is depressed rock-shaft 29 is turned sufficiently to cause arms 28 to engage arms 26 and push the carrier-frame forward to the limit of its forward movement, and when said arm 30 is released, spring 50 on shaft 29 and spring 23, hereinbefore referred to, will return the carrier-frame to the rearward limit of its movement. When it does this, it is necessary for pins 14, which have previously engaged the filing holes in the paper strips, to withdraw therefrom to prevent the strips from being buckled when the carrier-frame returns to the limit of its rearward movement. This I accomplish by means of a longitudinally reciprocable wedge 51 the upper flat side of which is held in sliding engagement with the underside of the platen by means of a screw 52 which extends down through a longitudinally elongated slot 53 in the rearward extension 54 of the wedge. The forward end of wedge 51 terminates (when at the limit of its rearward movement) a short distance to the rear of the forward end of the carrier-frame. A short distance back of its forward end the underside of the wedge is beveled or inclined downward and

- rearward and overlaps the rear edge of a transverse bridge 55, the ends of which latter are secured to springs 16. A short distance to the rear of its beveled surface, the 5 wedge is provided with a downward bifurcated lug 56 which engages the upper end of an arm 57 that extends upward from a boss that is loosely mounted upon the center of length of shaft 29. One side edge of the 10 boss of arm 57 is provided with a segmental slot or recess 58, and shaft 29 is provided with a pin 59 that projects into this recess 58. Bridge 55 has the forward ends of springs 16 bear down upon the same. When 15 shaft 29 is turned to move the carrier-frame forward it moves independently of arm 57 until pin 59 comes in contact with the lower terminus of recess 58, or in contact with the end of a gage-screw 60 tapped through the 20 lower portion of the boss of arm 57, whereupon said arm is moved and propels wedge 51 forward and moves bridge 55 and leaf-springs 16 downward. By the time the carrier-frame reaches the limit of its forward 25 movement, said pins will have been withdrawn from the perforations in the paper strips, and when this happens and the operator releases the pressure on arm 30 the carrier-frame immediately returns to the limit 30 of its rearward movement, and when pins 59 of shaft 29 engage the upper terminus of recess 58, wedge 51 is moved rearwardly to the limit of its rearward movement.
- It will be noticed that, owing to the manner in which arm 57 is actuated, the rearward movement of the wedge is delayed and thus keeps pins 14 at the limit of their downward movement until after said pins have moved to the rear of the filing openings of 40 the paper strips from which they were last withdrawn. In order to prevent the strips of paper from moving backward when thus released from said pins, and during the time the carrier-frame has been moving rearwardly independently of the wedge, a suitable rectangular tension-plate 61, whose upper horizontal edge extends up through a recess in the forward edge of the platen presses the paper toward tearing-blade 10. 45
- The lower edge of this tension-plate is provided with a knuckle that is loosely mounted upon a transverse stationary shaft 62 whose ends are secured in the side-frames of the register and the upper edge of said tension-plate is kept pressing against the paper in the manner just described by a spring 63 whose central yoke bears rearwardly against plate 61, and whose coiled ends are wound about said shaft 62. 50
- Heretofore the cover has been retained in its closed position over the platen by means of devices (not shown) located at the rear of the register frame. This has caused the forward end of the cover to be more or 55 less loose and given to vibrating vertically.
- By making the forward end of the cover stronger in the manner hereinbefore explained, it is possible to provide the end of the tearing-blade or end-member *c* opposite plunger 33 with a lug 37. A latch 38, 70 the lower end of which is pivoted to the side-frame of the register, is normally kept in engagement with said lug by a flat spring 39 whose lower end is secured by means of a suitable screw 40 to the nearest side-frame, 75 and the upper end of which engages a shoulder in the forward edge of the upper portion of the latch, substantially as shown. The movement of this latch is limited by pegs 41 and 42 projecting from said side-frame, substantially as shown, and the upper portion of the rear edge of the latch is beveled so that when the cover is closed down over the platen, lug 37 will force it forward until the shoulder of said latch snaps 80 over the same. 85
- In order to guide the paper strips so that as they are extracted the perforations will always align with pins 14, I have provided the side edges of platen B under the ends 90 of the tearing-blade with tongues 43, 43. These tongues are bent upward and when cover C is closed down over the platen they enter suitable longitudinally elongated recesses 45, 45 in the underside of the tearing-blade, substantially as shown in the drawings. 95
- The tearing-blade near each end is provided with peep-holes 4, 4, at the rear sides of slots 15 through which the tops of pins 100 14 can be seen when the cover is closed down over the platen to enable the operator to see that the pins engage the perforations in the paper strips when the required lengths thereof have been drawn out from between 105 the platen and tearing-blade.
- What I claim as new is:
1. In an autographic register, the combination with side-frames and a platen connecting the same, of a cover having a writing opening which is adapted to lock down over said platen and having a transverse member that overlies the discharge end of the platen and has its forward edge sharpened to constitute a tearing-blade for the 110 strips of paper extracted from said register, and a tension-plate engaging the underside of said tearing-blade. 115
  2. In an autographic register the combination with a platen and cover therefor the transverse end member of which overlying the discharge end of said platen being widened and constituting a tearing-blade, of pins for extracting strips of paper from the register that pass up through longitudinally elongated slots in said platen and engage said tearing-blade, and longitudinally movable means upon which said pins are mounted and movable therewith. 120
  3. An autographic register comprising a 130

platens the discharge end of which has longitudinally elongated slots therein, a cover for said platen the end member of which overlying said discharge end constitutes a 5 tearing-blade and which has longitudinal grooves in its underside that register with said slots, pins that pass up through said slots and move in said grooves and engage and extract paper strips from said register, 10 and longitudinally movable means upon which said pins are mounted.

4. In an autographic register, the combination with side-frames, and a platen connecting the same, of a cover having a writing opening therein adapted to lock down over said platen and having the end member thereof overlying the discharge end of the platen suitably widened and its forward edge sharpened to constitute a tearing-blade 20 for strips of paper extracted from said register, and means including vertically movable pins for extracting said strips from the register.

5. An autographic register comprising a platen, a cover for said platen the end member of which overlying the discharge end thereof constitutes a tearing-blade, longitudinally movable means, and pins carried thereby that are adapted to engage and extract paper strips from the register, a spring returnable rock-shaft, arms projecting therefrom that engage and move said means, another arm projecting from one end of said rock-shaft, a plunger vertically movable in 35 said cover and adapted to engage said last-mentioned arm.

6. An autographic register comprising a platen having longitudinally elongated slots in the discharge end edge thereof, an 40 open cover the end member of which overlying the discharge end of the platen is suitably widened and constitutes a tearing-blade, vertically movable pins adapted to engage paper strips passed over said platen, 45 longitudinally movable means by which said pins are carried, a spring returnable rock-shaft through the medium of which said means are moved, an arm projecting forward from one end of said shaft having 50 a flat tread on its outer end, and a vertically movable plunger reciprocable in an extension of said cover adjacent the discharge end of the register.

7. An autographic register comprising a 55 platen having longitudinally elongated slots in its forward end edge, a cover adapted to close down over said platen the forward end member of which overlying the discharge end of the platen is widened, a

blade secured to the underside of said end 60 member which constitutes a tearing-blade and which has longitudinally elongated grooves in the underside thereof in register with said slots, pins adapted to engage said slots and grooves to engage and extract 65 paper strips that pass between said platen and tearing-blade, longitudinally movable means upon which said pins are mounted, a transverse spring returnable rock-shaft through the medium of which said means 70 are reciprocated, an arm projecting forward from one end of said rock-shaft, and a plunger movable vertically in the extension of said cover and adapted to engage the forward end of said arm. 75

8. An autographic register comprising side-frames, a platen connecting the same which near its discharge end is provided with upwardly extending projections for guiding paper strips in transit over the 80 platen, vertically movable pins adapted to engage *seriatim* a longitudinally arranged series of perforations in said strips, and a tearing-blade under the ends of which said projections are located. 85

9. An autographic register comprising side-frames, a platen connecting the same which near its discharge end is provided with upwardly extending projections for guiding paper strips in transit over the 90 platen, vertically movable pins adapted to engage *seriatim* a longitudinally arranged series of perforations in said strips, and a cover for said platen the end member of which overlying the discharge end of the 95 platen being suitably widened and constituting a tearing-blade under whose end portions said projections are located when said cover is closed.

10. An autographic register comprising a 100 platen the discharge end of which has longitudinally elongated slots therein, of a cover for said platen the end member of which overlying said discharge end is suitably widened and constitutes a tearing-blade, 105 pins carried thereby that pass up through said slots and engage and extract paper strips from the register, and longitudinally movable means upon which said pins are mounted; said tearing-blade being provided 110 with holes therein through which said pins can be seen when said cover is closed.

In witness whereof I have hereunto set my hand this 23rd day of August, 1916.
ENGLAND J. BARKER.
